US0D1063682S

(12) **United States Design Patent** (10) **Patent No.:** **US D1,063,682 S**
(45) **Date of Patent:** **** Feb. 25, 2025**

(54) **RING**

(71) Applicant: **LOUIS VUITTON MALLETIER**,
Paris (FR)

(72) Inventors: **Francesca Amfitheatrof**, Paris (FR);
Paul Harrison, Paris (FR); **Naomi**
Brown, Paris (FR)

(73) Assignee: **Louis Vuitton Malletier**, Paris (FR)

(**) Term: **15 Years**

(21) Appl. No.: **29/859,211**

(22) Filed: **Nov. 8, 2022**

(30) **Foreign Application Priority Data**

May 12, 2022 (FR) 20222134

(51) **LOC (15) Cl.** **11-01**

(52) **U.S. Cl.**

USPC **D11/34**

(74) Attorney, Agent, or Firm — Fross, Zelnick, Lehrman & Zissu, P.C.; Charles T. J. Weigell, Esq.

(57) **CLAIM**

The ornamental design for ring as shown and described.

DESCRIPTION

FIG. 1 is a perspective view of ring showing our new design;
FIG. 2 is a front view thereof;
FIG. 3 is a back view thereof;
FIG. 4 is a right side view thereof;
FIG. 5 is a left side view thereof;
FIG. 6 is a top view thereof; and,
FIG. 7 is a bottom view thereof.

1 Claim, 7 Drawing Sheets
